(57) **CLAIM**

(21) Appl. No.: **29/123,571**

The ornamental design for a surface contour for a computer housing, as shown and described.

(22) Filed: **May 19, 2000**

DESCRIPTION

(51) LOC (7) Cl. **14-02**

FIG. 1 is a top, front and right side perspective view of a surface contour applied to a computer housing showing my new design;

(52) U.S. Cl. **D14/439**

FIG. 2 is a front elevational view thereof; and,
FIG. 3 is a top plan view thereof.

(58) Field of Search D14/432, 439,
D14/440, 441, 314, 349, 356, 363; 361/679-87,
600, 622, 627-36, 724-5; 200/5 R, 5 A,
6 R, 6 A; D13/184, 199

The broken line drawing of the remainder of the computer housing in all views is for illustrative purposes only and forms no part of the claimed design.
